UNITED STATES PATENT OFFICE.

HERMAN E. TAYLOR, OF DETROIT, MICHIGAN.

TRANSPORTATION SYSTEM.

Application filed October 6, 1924. Serial No. 742,002.

The invention relates to transportation systems or the like and has among its objects to provide means for cheaply and rapidly transporting a large number of passengers. A further object is to provide a rapid transportation system which includes a pair of endless moving platforms, one of which is operated continuously at a predetermined speed while the other platform is alternately slowed down to receive or discharge passengers and then operated at substantially the speed of the other platform to transfer the passengers from or to the last said platform from or to the first said platform. A further object of the invention is to provide gates which are adapted to be automatically opened and closed at the proper times for permitting the passengers to board the platforms and leave the same. A further object of the invention resides in the provision of a novel means for propelling the platforms, such means including helices adapted to receive pins or the like secured to the platforms. With these and other objects in view, the invention resides in the novel features of construction and combinations and arrangements of parts as more fully hereinafter described and claimed.

Referring to the drawings:

Figure 1 is a diagrammatic plan of one embodiment of my invention showing one of the driving units in relation to the platforms;

Figure 2 is a diagrammatic view in elevation showing the relation of the helix for driving the variable speed platform and the pins for effecting such drive;

Figure 3 is a view corresponding to Figure 2 showing diagrammatically the manner of varying the pitch of the helices for varying the speed of the variable speed platform;

Figure 4 is a sectional view in elevation through the platforms and helices;

Figure 5 is a fragmentary view of the forward end of the variable speed driving helix;

Figure 6 is a like view showing an intermediate portion of the same helix;

Figure 7 is a view showing a portion of the same helix in cross section in relation to the various pins carried by the variable speed platform;

Figure 8 is a plan view of a portion of the platforms;

Figure 9 is a detail plan view illustrating the manner of connecting together the units of the platform;

Figure 10 is a sectional view in elevation along the line 10—10 of Figure 9;

Figure 11 is an enlarged detail view showing the supporting means for the platforms;

Figure 12 is a diagrammatic view showing one of the drive units;

Figure 13 is a fragmentary view in elevation showing the gate operating means for the platforms;

Figure 14 is a detail plan view of the rack bar which causes the simultaneous operation of the gates;

Figure 15 is a view of the actuating rack along the line 15—15 of Figure 13;

Figure 16 is a sectional view in elevation along the line 16—16 of Figure 14, and

Figure 17 is a sectional elevation view along the line 17—17 of Figure 14 after the rack bar has been actuated.

In the drawings reference character A indicates the inner endless platform or high speed platform formed of a plurality of platform members or units 10. B indicates the outer endless platform or variable speed platform formed of the platform members or units 11. The platforms A and B are adapted to be driven in the direction of the arrow shown in Figure 1 by means of a plurality of helices C and D respectively located beneath the platforms and spaced at intervals along the length thereof. In order to rotate each adjacent pair of helices C, D, I provide a motor 12 (Figures 1 and 12) adapted to rotate a shaft 13 secured to the forward end of which is a pinion 14. 15 and 16 are respectively gears mounted on the helices C and D and driven by the pinion 14. A bevel gear 17 is mounted on each shaft 13 and, as shown in Figure 1, each opposite pair of helices C, D, comprises a drive unit (Figure 12) synchronized by reason of the cross shaft 18 carrying bevel gears 19 meshing with the bevel gears 17. The cross shaft 18 also permits either motor of each drive unit to operate both pairs of helices C, D should the other motor become 105 inoperative for any reason. The helices D are formed with the reduced portions D' the purpose of which will be presently apparent.

For driving the endless platforms A and B I provide drive pins 20 adapted to engage the helices C and D. The platform

members 10 and 11 are connected as shown in Figures 9 and 10. In these views the adjoining ends of the platform members 10 are shown arcuately formed in order to permit the platform to follow a curve. The ends of the platform units are also provided with overlapping tongues 21 for forming a close connection between the successive platform members. Beneath the platform members is a coupling bar 22 secured at one end to one of the platform members 10 by the bolts 23 and at the opposite end is connected to the adjacent platform member by a bolt 24 about which the latter platform member pivots when making a turn. The bolt 24 is adapted to be held in place by a nut 25 resting on a split bearing plate 26 beneath which is a split collar 27. The coupling bar 22 is adapted to carry the drive pins 20 as shown. The platform members 11 are similarly connected together.

In order to cause the variable speed platform B to alternately slow down and speed up, each helix D is provided with a portion 25 D' reduced in diameter. The pitch of the helices of this reduced portion is adapted to become gradually less until the platform B driven therefrom would be slowed down sufficiently to permit passengers to board this 30 platform or leave the same in a manner presently described.

The pitch of the helix is constant thereafter for a sufficient distance to permit passengers to board or leave and then the pitch 35 gradually increases until the variable speed platform is again driven at the same speed as the high speed platform A.

It should be understood that the motors 12 and gears 14, 15 and 16 are adapted to 40 rotate, at all times, the helices C, and D at the same constant angular velocity.

In order to permit the variable speed platform B to be driven at only one point from each of the spaced helices D during the 45 period that the platform B is changing its speed, the drive pins 20 of this platform are of sufficient length to engage only the part of the helix having the large diameter, the pins passing clear of engagement with the portion D' of decreased diameter. Spaced 50 at predetermined intervals (determined by the desired frequency of slowing down of the platform B) I provide a long pin 28 of sufficient length to engage the helix D 55 throughout the length thereof. At the rear of each long pin 28 I provide guide pins 29 between the adjacent platform members instead of the drive pins 20. The guide pins 60 the purpose of which will be presently apparent are of sufficient number to pass clear of the helix D while the long pins 28 are in engagement with the portions of helix D that drive the variable platform at a speed less than that of the high speed platform A. In this manner it will be apparent

that the entire platform B is periodically driven by engagement of the long pins 28 (at which times the platform B is slowed down and then speeded up) and the drive pins 20 (at which times the platform B is 70 driven at a speed equal to that of the high speed platform A).

Referring to Figures 5 and 6 the helix D is formed with a groove 30 of constant diameter throughout. In order to form the reduced portion D' of the helix the walls 31 of the groove (see Figure 7) are cut away as indicated at 32. Thus in Figure 7 it will be noted that the guide pins 29 clear the helices D at all times, while the drive 80 pins 20 of the platform B engage only the first part of the helices D having the large diameter passing free of the portion D' of decreased diameter. The guide pins 29 pass free of the helices at all times. The 85 drive pins 28 engage all parts of the helices D and cause the platform B to vary in its speed as explained above.

Referring to Figure 4 I have shown my transportation system in the nature of a 90 subway formed by the walls 33. Each of the platforms A and B is movably supported on rollers 34 which run in tracks 35 supported at suitable intervals by the yoke-like supporting frame 36. The rollers 34 95 have their axles 37 journaled in the longitudinally extending portions 38 of the yokes 39. Successive yokes are connected by a cable or the like 40. In order to guide the upper faces of the rollers 34 the guide bars 41 are provided, supported at intervals throughout the length of the track by brackets 42 bolted or otherwise carried by the tracks 35. The tracks 35 extend in endless fashion beneath the platforms, the rollers 34 100 105 being connected by cables 40 and being free to travel around the track as the platforms are moved.

Figure 4 illustrates the manner of supporting the helices C and D, the former being 110 comparatively short is supported at its ends by bearings 43 supported by brackets 44, while the latter although supported at its ends in a similar manner is additionally supported between its ends the portion D' by 115 bearing rollers 45 supported by brackets 46, the rollers 45 preferably extending substantially the pitch of the helix D as shown in Figure 6.

Guide rails 50 are adapted to receive the 120 guide pins 29 as well as the pins 28 and 20, the guide pins 29 serving to guide the platform B at the periods of non-engagement of pins 20 with the helix D.

The high speed platform A is formed, as 125 shown in Figures 4 and 8, with seats 47 located in transverse aisles formed by the arches 48 preferably constructed of jointed pipe sections and provided with the connecting pipe sections 49.

At the side of platform A adjacent the variable speed platform B I provide pairs of gates 51 and 52 rotatably supported on the gate posts 53 and 54 respectively, the 5 latter posts extending through the floor of the platform A and respectively carrying actuating pinions 55 and 56. The latter pinions are actuated by an arcuate rack 57 having teeth 58 engaging pinion 55 and 10 teeth 59 engaging pinion 56. Rack 57 is supported from the bottom face of platform A by a pivot pin 60, the rear of each rack 57 having also a downwardly extending pin 58 engaging a U-shaped channel 61 of rack bar 62 which extends throughout the length 15 of the platform A. The rack bar 62 is slidably guided at intervals throughout its length by the brackets 63. The rack bar is also provided at frequently occurring intervals with racks 64 meshing with pinions 65 which support the rack bar 62 by engagement of pinions 65 with stationary racks 66. Pinions 65 are secured to a shaft 67 extending throughout the length of the rack bar 62 whereby the latter is moved laterally at all points as a unit in a manner to be described. In order to move the rack bar 62 to actuate arcuate racks 57 and open and 20 close the gates 51, 52 at suitable points, I provide actuating pins 68 carried by the platform units 11 of platform B. The pins 68 preferably occur at the point of each long pin 28 and are adapted to engage a cam face 69 to shift the rack bar 62 to the right as viewed in Figure 4 whereby the 25 racks 57 are rotated on pivot pins 60 to open gates 51, 52 to the position indicated by the dotted lines 70 in Figures 4 and 8. After the gates have remained open for a desired 30 length of time the actuating pins 68 in the course of their forward travel engage the return cam faces 71 which serve to return the rack bar 62 to the original position, thus shutting the gates 51, 52 to the position 35 shown in Figure 13.

The variable speed platform B is formed with transverse aisles formed by arches 72 aligned with arches 48 of platform A and likewise preferably constructed of jointed pipe sections having connecting pipe sections 73.

The platform B is provided with pairs of gates 74, 75 constructed similar to the gates 51, 52 of platform A and adapted to be actuated by similarly constructed arcuate racks 57. There is the difference however, in that the spaced actuating pins 68' of the platform B are carried by the latter platform, the pin 68' engaging cam faces corresponding to 69 and 71 for opening and closing the gates respectively. The cam faces are also considerably steeper than those for the platform A since the gates of platform B are actuated when the platform (and the actuating pins 68' carried thereby) is mov-

ing at a considerably less speed than that of the high speed platform A, as will be apparent from the following description of the operation.

In describing the operation of the transportation I will illustrate the same by giving a specific example of the speed at which the platforms A and B may travel, as well as the distances travelled and general dimensions of some of the essential elements 70 of my invention. The following figures are merely for illustrative purposes however and may be varied to suit conditions as desired.

While my transportation system is adapted 80 to operate on the surface or as an elevated system, I prefer to operate the same underground between points E and F, for example, which might represent the downtown or business district of a city and the up-town or residential section respectively, the distance between points E and F being 16 miles, for example. The platforms A and B in their travel uptown and downtown 85 preferably are located beneath the sidewalks 90 respectively of a main thorofare connecting points E and F, the platforms A and B being formed endless fashion by the units 10 and 11 respectively. The platform units 10 and 11 are preferably 12 feet long constituting equally divisible units of each mile of the platform, i. e., 440 units to each mile. At intervals of one-half mile I provide a driving unit as shown in Figure 12. The motors 12 rotate the helices C and D so that 95 the platform A is continuously advanced at the rate of thirty miles per hour by engagement of drive pins 20 with helix C. The pitch of helix C is preferably 12 feet so that for each revolution of the helix the platform C is advanced the length of one unit 100. It is thus obvious that the platform A is subjected to a propelling influence by continuous engagement of two drive pins 20, (the length of helix C being substantially 105 24 feet) at every one-half mile. Inasmuch as the platform A is constructed of the connected units 10 it is therefore apparent that this platform will at all times be driven at a speed of thirty miles per hour, the coupling bars 22 connecting successive platforms 10 being provided with drive pins 20 throughout the length of platform A.

The platform B is provided with a long 110 pin 28 preferably every $\frac{1}{8}$ mile, each long pin 28 being followed by 17 guide pins, the length of the helix D being 216 feet or 18 platform units.

The portion D' of helix D preferably 125 constitutes 192 feet or 16 platform units, leaving a length of 24 feet for engagement with the drive pins 20 and long pins 28 of platform B. Considering the distance between each long pin 28 to be $\frac{1}{8}$ mile or 660 feet 130 or 55 platforms, behind each long pin 28 is

17 guide pins followed by 37 drive pins 20 making a total of 55 pins for each $\frac{1}{8}$ mile.

Starting with the parts as shown in Figures 2, 3 and 5 in which a long pin 28 is just entering the helix D, both of the platforms A and B will be driven in the same direction and at the same speed of thirty miles per hour. Bearing in mind the fact that the angular velocities of the helices A and B always remain constant it is apparent that by gradually reducing the pitch of the helix portion D' the speed of the platform B will be correspondingly reduced.

As each long pin 28 engages the helix D, every fourth long pin is also simultaneously engaging one of the helices D since, as aforesaid, the long pins are spaced every $\frac{1}{8}$ mile while the helices are spaced in one-half mile intervals.

Tracing a cycle of the operation from the point where each long pin engages the first part of helix D, the latter being provided with a mouth portion 76 formed by cutting away the wall of the helix in order to readily accommodate the pins in starting their course of travel along the helix, the long pin 28 engages the helix D for a distance of twenty-four feet or two units at the speed of thirty miles per hour, the platforms A and B travelling at the same speed. As the long pin reaches the point G, Figure 3, (the drive pins 20 ahead of the long pin are passing clear of the portion D' and the guide pins 29 at the rear of the long pin are also free of engagement of the helix D) the pitch of the helices of the portion D' begins to gradually decrease up to the point H during which interval the platform B will decrease in speed from thirty miles per hour to eight tenths miles per hour, the latter speed permitting passengers to safely board the platform B at any point from the stationary loading platform 77 (Figure 4) which entirely surrounds the platform B. The long pin 28 from the point H drives the platform B at the speed of eight tenths miles per hour for a distance of twelve feet, or the length of one unit, until the joint J is reached. From the point J to the point K the pitch of the helix gradually increases until at the point K the platform B is again being driven at a speed of thirty miles per hour. As the long pin travels the length (12 feet) of the remainder of the helix, the drive pins 20 again start to engage the first portion of the helix D and will continue to do so and drive the platform B at a speed of thirty miles per hour until the next long pin engages the helix D, at which time the cycle will be repeated. It should be noted that the performance at each helix is the same throughout the system as must necessarily be the case to make all portions of the platform B slow down and speed up at the same time.

Before describing the operation of the gates their function is readily understood when the performance of the platforms A and B are described in relation to receiving and discharging passengers. When the platform B is running at the low speed of eight tenths miles per hour the gates of the units 11 swing open whereby passengers may board platform B at any point throughout its entire length. As platform B speeds up these gates close and when the platform B reaches the speed of platform A, the latter running continuously at thirty miles per hour, the gates of the platform A swing open and the passengers on platforms B pass to platform A where they take the seats 47 on this latter platform. At the same time passengers on platform A desirous of leaving the platforms pass from platform A to platform B where they wait until this latter platform again is slowed in speed to eight tenths miles per hour and the gates open to permit boarding and discharge of passengers to and from the platform B. Just before the platform B reduces its speed from that of platform A the gates of the latter close to prevent further passage of passengers between the two platforms.

Following again the cycle of travel of any long pin 28 longitudinally of the helix D with respect to the operation of the gates, as each long pin reaches the point G each actuating pin 68 engages the return cam faces 71 or rack bar 62 whereby the gates 51, 52 of the high speed platform A begin to close by reason of the rocking movement imparted to the gate posts 53, 54 actuated through pinions 55 and 56 respectively, the pinions being rotated by the rack 57 having the pin 58 moved by the channel 61 of the rack bar 62. When the long pin reaches a point indicated at L the gates of the high speed platform A will be closed. It will be noted that the platform B is decreasing in speed at this time. When the long pin reaches the point M the gates 74, 75 of the variable speed platform B start to open, the gates being opened by engagement of pins 68' with the cam face 69 of the rack bar. As before stated these pins 68' cause lateral movement of the rack bar 62' the latter during its movement rotating spaced pinions 65 and shaft 67. The latter shaft transmits the rotative effort to the pinions 65 which are located between successive pins 68' in order to insure proper movement of the rack bar at frequent intervals. Thus the gates of the variable speed platform B are opened beginning at point M, the gates being entirely opened when the long pin reaches the point H. From the points H to J the gates 74, 75 remain open permitting passengers to board and leave the platform B from and for the loading platform 77 at all points adjacent the platform B. When the long pin reaches the point J

the gates 74, 75 of the variable speed platform B start to close by engagement of the pins 68' with the return cam faces 71, and at the point N these gates are closed preventing further boarding or leaving the platform B.

On reaching the point O the gates 51, 52 of the high speed platform A begin to open, by reason of the pins 68 acting on the cam faces 69 of the rack bars 62 as previously described. At the point K the gates 51, 52 are open at which time passengers from the platform A pass to the platform B where they take the seats 47 and remain until they desire to leave. At the same time passengers about to reach their destination pass from the platform A to the platform B where they await the next slowing down of the latter platform in order to leave the same. The gates 51, 52 remain open until the long pin nearest the next helix D reaches the point G of the said next helix D, whereupon the cycle is repeated.

Admission of passengers to the loading platform 77 may be regulated in any desired manner, as by collecting fares in the customary manner of the subway systems now used in many large cities. Passengers leaving the platform 77 may also be regulated by the usual exits (not shown) or in any manner desired. If desired the system could be arranged to collect the fares of passengers upon leaving the platform 77. At any rate it is apparent that I have invented means for entirely avoiding the necessity of employed attendants on the platforms A and B, the variable speed platform operating in an entirely automatic manner. The gates of the platforms A and B are likewise automatic in their operation.

It is obvious that the long pins 28 may be spaced at any intervals desired, the spacing being determined by the frequency of the periods of slowing down of the platform B. In a like manner the helices C, D may be spaced at any desired intervals. While I have illustrated and described various values for the speeds, distances, dimensions, etc., of the various parts of the system it is obvious that these values can be changed to suit various conditions.

While it is believed that from the foregoing description, the nature and advantages of my invention will be readily understood, I desire to have it understood that I do not limit myself to what is herein shown and described and that such changes may be resorted to when desired as fall within the scope of the claims.

What I claim as my invention is:

1. A transportation device comprising a platform, means for moving said platform at a constant relatively high speed, a second platform adjacent the first and means for moving the second platform as a unit throughout its length alternately at substan-

tially the same speed of the first platform and then at a relatively low speed.

2. A transportation device comprising a high speed platform and a variable speed platform and means for moving the latter 70 platform as a unit alternately at speeds approximating the former and at relatively low speeds.

3. A transportation device comprising a high speed platform, means for moving the 75 platform at a constant speed, a variable speed platform, means permitting passengers to board the latter platform only when it is moving at a relatively slow speed and means permitting passengers to move therefrom to the high speed platform only when the two said platforms are moving at substantially the same speed.

4. A transportation device comprising a platform, means for moving said platform 85 at a constant speed, a second platform adjacent the first, means for moving the second platform as a unit at a relatively low speed and means for moving the second platform as a unit at a relatively high speed.

5. A transportation device comprising a platform, means for moving said platform at a constant speed, a second platform adjacent the first, means for moving the second platform at times as a unit at a relatively low speed permitting passengers to board the same at any point throughout the length thereof and means for thereafter moving the same platform at a speed permitting said passengers to transfer from the second platform to the first said platform.

6. A transportation device comprising a platform, means for moving the same at a constant relatively high speed, a second platform, means for moving the second platform at varying speeds simultaneously throughout the length thereof, means for permitting passengers to board and leave the second platform simultaneously at a plurality of points throughout the length thereof when the latter is running at a relatively low speed and means permitting passengers to pass from either one of said platforms to the other simultaneously at a plurality of points throughout the lengths of the said platforms when the second said platform is running at a relatively high speed.

7. A transportation device comprising an endless platform, means for driving the same at a constant speed, a second endless platform adjacent the first, means for driving the second platform as a unit at variable speeds permitting passengers to transfer to and from the first platform by way of the second platform.

8. A transportation device comprising a platform, means for operating said platform at a constant relatively high speed, a second platform and means for operating the

same at a variable speed whereby passengers may be transferred to and from the high speed platform simultaneously at substantially all points throughout the length of 5 the high speed platform by way of the variable speed platform.

9. A transportation device comprising a plurality of platform units connected together to form an endless platform, a second platform similarly constructed, means for operating the first platform at a constant relatively high speed simultaneously at all points thereof and means for operating the second said platform at speeds 10 simultaneously at all points thereof permitting transfer of passengers to and from the first said platform by way of the second.

10. A transportation device comprising a stationary loading platform, a variable speed platform adjacent the said loading platform, a high speed platform adjacent the variable speed platform, means for driving the same at a constant speed, and means for driving the variable speed platform at uniform speeds throughout its length to permit transfer of passengers thereto from the loading platform and therefrom to the said high speed platform.

11. A transportation device comprising a stationary loading platform, a variable speed endless platform adjacent the said loading platform, a high speed endless platform adjacent the variable speed platform, means for driving the same at a constant speed, and means for driving the variable speed platform to permit transfer of passengers thereto from the loading platform and therefrom to the said high speed platform simultaneously at substantially all 30 points of the variable speed platform.

12. A transportation device comprising a stationary loading platform, a platform adjacent thereto, driving means for said platform whereby the latter is alternately 45 speeded simultaneously at all points throughout its length up to a relatively high speed and slowed down simultaneously at all points throughout its length to a relatively low speed, a second platform adjacent the first said platform, driving means for the second platform whereby the latter is driven at a constant relatively high speed, means permitting passengers to pass between the first said platform and the loading platform at times when the first said platform is being driven at its said relatively low speed, and means permitting passengers to pass between the said first and second platforms at times when the first said platform is being driven at its said relatively high speed.

13. A transportation device comprising a stationary loading platform, a platform adjacent thereto, driving means for said platform whereby the latter is alternately 60

speeded up to a relatively high speed and slowed down to a relatively low speed, a second platform adjacent the first said platform, driving means for the second platform whereby the latter is driven at a constant relatively high speed, means permitting passengers to pass between the first said platform and the loading platform at times when the first said platform is being driven at its said relatively low speed, and means permitting passengers to pass between the said first and second platforms at times when the first said platform is being driven at its said relatively high speed, and automatically operated means limiting the passage of passengers between the points aforesaid to the times when the speeds of the said platforms bear the aforesaid relations. 70

14. A transportation device comprising a stationary loading platform, a platform adjacent thereto, driving means for said platform whereby the latter is alternately speeded up to a relatively high speed and slowed down to a relatively low speed, a second platform adjacent the first said platform, driving means for the second platform whereby the latter is driven at a constant relatively high speed, means permitting passengers to pass between the first said platform and the loading platform at 80 times when the first said platform is being driven at its said relatively low speed, and means permitting passengers to pass between the said first and second platforms at times when the first said platform is being driven at its said relatively high speed, and automatically controlled gates for limiting the passage of passengers between the points aforesaid to the times when the speeds of the said platforms bear the aforesaid relations. 90

15. A transportation device comprising a stationary loading platform, an endless platform adjacent thereto, said platform having spaced pins, a helix below the platform adapted to be engaged by said pins for driving the platform therefrom, a second endless platform adjacent the first and provided with pins, a second helix below the second platform adapted to be engaged by the last said pins for driving the second platform therefrom, means for driving said helices at the same constant angular velocity, means associated with said first helix adapted to drive its platform at relatively 100 low speeds at times and relatively high speeds at other times, means associated with said second helix for driving its platform at a constant relatively high speed substantially equal to that of the said high speed of the first platform, means permitting passengers to pass between the said first and second platforms at times when the first said platform is being driven at its said relatively high speed. 105

110

115

120

125

130

16. A transportation device comprising a stationary loading platform, an endless platform adjacent thereto, said platform having spaced pins, a helix below the platform adapted to be engaged by said pins for driving the platform therefrom, a second endless platform adjacent the first and provided with pins, a second helix below the second platform adapted to be engaged by the last said pins for driving the second platform therefrom, means for driving said helices at the same constant angular velocity, means associated with said first helix adapted to drive its platform at relatively low speeds at times and relatively high speeds at other times, means associated with said second helix for driving its platform at a constant relatively high speed substantially equal to that of the said high speed of the first platform, means permitting passengers to pass between the said first and second platforms at times when the first said platform is being driven at its relatively high speed, and automatically operated means limiting the passage of passengers between the points aforesaid to the times when the speeds of the said platforms bear the aforesaid relations.
17. A transportation device comprising a stationary loading platform, an endless platform adjacent thereto, said platform having spaced pins, a helix below the platform adapted to be engaged by said pins for driving the platform therefrom, a second endless platform adjacent the first and provided with pins, a second helix below the second platform adapted to be engaged by the last said pins for driving the second platform therefrom, means for driving said helices at the same constant angular velocity, means associated with said first helix adapted to drive its platform at relatively low speeds at times and relatively high speeds at other times, means associated with said second helix for driving its platform at a constant relatively high speed substantially equal to that of the said high speed of the first platform, means permitting passengers to pass between the said first and second platforms at times when the first said platform is being driven at its relatively high speed, and automatically operated means limiting the passage of passengers between the points aforesaid to the times when the speeds of the said platforms bear the aforesaid relations.
18. A transportation device comprising a platform, a helix below said platform said helix formed with a groove of varying pitch, a pin carried by said platform for periodically engaging said helix for driving the platform at various speeds, and other pins carried by said platform adapted to engage said helix for driving the platform at a constant speed at other times.
19. In a transportation device, a movable platform, a plurality of gates for controlling exit and entrance passages from and to said platform, means for automatically moving said gates to open and close the same at predetermined intervals, said means comprising a bar extending longitudinally of said platform, connections between said bar and said gates and means for shifting said bar transversely of said platform to act upon said connections to swing said gates to open and closed positions.
20. In a transportation device, a movable platform, a plurality of gates for controlling exit and entrance passages from and to said platform, and means for automatically moving said gates to open and closed position at predetermined positions of said platform.

In testimony whereof I affix my signature.

HERMAN E. TAYLOR.
